UNITED STATES PATENT OFFICE.

EDWARD BUTTS, OF GEORGETOWN, COLORADO, AND HARRY K. DEAN, OF BOSTON,
MASSACHUSETTS.

RAILWAY TIE.

Application filed May 25, 1922. Serial No. 563,619.

To all whom it may concern:

Be it known that we, EDWARD BUTTS, a citizen of the United States, residing at Georgetown, in the county of Clear Creek 5 and State of Colorado, and HARRY K. DEAN, a citizen of the United States, residing at Boston, in the county of Suffolk and State of Massachusetts, have invented new and useful Improvements in Railway Ties, of which

10 the following is a specification.

This invention relates to a railway tie and has for its object to provide an improved construction whereby a rail may be held securely to a metal tie.

15 Another object of the invention is to provide an improved construction of cushion block to be inserted between the rail and the tie, said cushion block being so constructed that it may be easily inserted within the tie 20 beneath the rail or removed therefrom, and when in place in said tie, will be securely held and prevented from becoming accidentally loosened.

25 The invention consists in the combination and arrangement of parts set forth in the following specification and particularly pointed out in the claims thereof.

Referring to the drawings:

30 Figure 1 represents a plan view of a railway tie embodying the invention, a portion of two rails being illustrated attached thereto.

Fig. 2 is a side elevation of the railway tie, the rails being illustrated in section.

35 Fig. 3 is a transverse section through the railway tie as taken on the line 3—3 of Fig. 2.

Fig. 4 is a vertical section partly in elevation taken on the line 4—4 of Fig. 1.

40 Fig. 5 is a plan view of an end portion of the railway tie.

Fig. 6 is a perspective view of a cushion block.

45 Fig. 7 is a perspective view of a clamping member.

Fig. 8 is a sectional elevation similar to Fig. 4 but illustrating a modified embodiment of the invention.

Like numerals refer to like parts throughout the several views of the drawings.

In the drawings, referring to Figs. 1 to 7 inclusive, 10 represents a railway tie con-

structed of metal and having a flat base portion 11 and a centrally disposed longitudinal rib 12. Located a suitable distance apart 55 upon the tie 10 are enlarged portions 13 in which transversely extending tapered grooves 14 are provided. The grooves 14 are in turn provided intermediate their length with oppositely disposed recesses 15. 60 Located in each tapered groove 14 is a tapered block 16 of wood, or other suitable material which forms a support for a rail 17 of the usual well known type which rests thereon. The block 15 is illustrated in detail in Fig. 6 and said block forms a cushion between the rail 17 and tie 10 and acts to absorb the vibrations caused by the movement of trains over the rails 17.

The rails 17 are secured upon the cushion block 16 and to the tie 10 by clamping members 18 which are located in the recesses 15 and slide vertically therein. The clamping members 18 are provided with a flange 19 formed integral therewith which overlies 75 and engages the flanges of the rails 17. The clamping members 18 are also provided with a spur 20 formed integral therewith and when the clamping member is forced downwardly in its recess, the spur 20 penetrates 80 the cushion block 16 as illustrated in Fig. 4 and thereafter prevents movement of the latter transversely of the tie, thereby securely holding said cushion block in the groove 14. The clamping member 18 is itself 85 securely held in position in the recess 15 with its flange 19 in engagement with the flange of the rail 17 and its spur 20 penetrating the cushion block 16 by a bolt 21, nut 22 and lock nut 23, the head of said bolt being located in a recess 24 provided in the under surface of the tie 10 and said bolt projects upwardly through said tie and through 90 said clamping member, the nut 22 contacting with the upper surface of the clamping member 18. It is evident that any of the well known types of lock washers in common use may be utilized in connection with either of the nuts 22 or 23 to prevent the accidental loosening of the same upon the 95 bolt 21.

The device herewith illustrated and described can be easily constructed and quickly installed, is practically indestructible and

will therefore last indefinitely. The cushion blocks 16 give the flexibility required and are the only parts which require replacing, and their construction is such that they 5 can be easily removed from the tie without disturbing either tie or rail. The cushion block is held firmly in position within the tie by means of the clamping blocks 18 and spurs 20 formed thereon. No spikes are 10 driven through the cushion blocks to cause decay in the wood and there is no chance in the device for the clamping members and bolts to become loosened through decay of any of the parts, thereby making it impossible 15 for the rails to spread.

In Fig. 8 a modified embodiment of our invention is illustrated in which a layer of resilient cushioning material 25, as, for example, rubber is located within the groove 20 14 of the tie 10 between the tapered cushion block 16 and the upper surface of the groove 14. All the other parts of the device are exactly as illustrated and described in connection with Figures 1 to 7 inclusive. The 25 provision of the layer of material 25 gives a greater cushioning support for the rails 17.

We claim:

1. A railway tie having, in combination, 30 a metal body portion provided with grooves extending transversely thereof, said grooves having recesses formed in the opposite sides thereof, a cushion block located in each groove, a clamping member mounted in each 35 recess and located upon opposite sides of said cushion block and means to hold said clamping member in engagement with a rail mounted upon said cushion block.

2. A railway tie having, in combination, a 40 metal body portion provided with grooves extending transversely thereof, said grooves having recesses formed in the opposite sides thereof, a cushion block located in each groove, a clamping member mounted in each 45 recess and located upon opposite sides of said cushion block and engaging the latter to prevent movement thereof transversely of the tie and means to hold said clamping member in engagement with a rail mounted 50 upon said cushion block.

3. A railway tie having, in combination, a metal body portion provided with tapered grooves extending transversely thereof, said grooves having recesses formed in the opposite sides thereof, a tapered cushion block located in each groove, a clamping member mounted in each recess and located upon opposite sides of said cushion block and means to hold said clamping member in engagement with a rail mounted upon said cushion block.

4. A railway tie having, in combination, a metal body portion provided with grooves extending transversely thereof, said grooves 60 having recesses formed in the opposite sides

thereof, a cushion block located in each groove, a clamping member mounted in each recess and located upon opposite sides of said cushion block, said clamping member embodying therein a flange adapted to engage the flange of a rail mounted upon said cushion block and means to hold said clamping member in engagement with said rail. 70

5. A railway tie having, in combination, a metal body portion provided with grooves extending transversely thereof, said grooves having recesses formed in the opposite sides thereof, a cushion block located in each groove, a clamping member mounted in each recess and located upon opposite sides of 80 said cushion block, said clamping member embodying therein a flange adapted to engage the flange of a rail mounted upon said cushion block, said clamping member also embodying therein a spur engaging said 85 cushion block to prevent a movement thereof transversely of said tie and means to hold said clamping member in engagement with said rail and cushion block.

6. A railway tie having, in combination, 90 a metal body portion provided with grooves extending transversely thereof, said grooves having recesses formed in the opposite sides thereof, a cushion block located in each groove, a clamping member mounted in each 95 recess and located upon opposite sides of said cushion block, said clamping member embodying therein a flange adapted to engage the flange of a rail mounted upon said cushion block, said clamping member also embodying therein a spur engaging said 100 cushion block to prevent a movement thereof transversely of said tie and bolts extending through said tie and clamping member and holding the latter in engagement with 105 said rail and cushion block.

7. A railway tie having, in combination, a main body portion provided with tapered grooves extending transversely thereof, said grooves having recesses formed in the opposite sides thereof, a tapered cushion block located in each groove, a clamping member mounted in each recess and located upon opposite sides of said cushion block, said 110 clamping member embodying therein a flange adapted to engage the flange of a rail mounted upon said cushion block, said clamping member also embodying therein a spur engaging said cushion block to prevent a movement thereof transversely of said tie 115 and means to hold said clamping member in engagement with said rail and cushion block.

8. A railway tie having, in combination, a metal body portion provided with grooves extending transversely thereof, said grooves 120 having recesses formed in the opposite sides thereof, a cushion block located in each groove, a layer of resilient material located in each groove beneath said cushion block, a clamping member mounted in each recess 125

65 having recesses formed in the opposite sides 130

and located upon opposite sides of said cushion block, said clamping member embodying therein a flange adapted to engage the flange of a rail mounted upon said cushion block, 5 said clamping member also embodying therein a spur engaging said cushion block to prevent movement thereof transversely of said

tie and means to hold said clamping member in engagement with said rail and cushion block. 10

In testimony whereof we have hereunto set our hands:

EDWARD BUTTS.
HARRY K. DEAN.
